UNITED STATES PATENT OFFICE.

JAMES J. BUSH, OF NEW YORK, N. Y.

STEAM-GENERATOR.

SPECIFICATION forming part of Letters Patent No. 744,900, dated November 24, 1903.

Application filed March 30, 1903. Serial No. 150,124. (No model.)

To all whom it may concern:

Be it known that I, JAMES J. BUSH, a citizen of the United States, residing at New York, in the county of New York and State of New York, have invented certain new and useful Improvements in Steam-Generators, of which the following is a specification, such as will enable those skilled in the art to which it appertains to make and use the same.

This invention relates to improvements in steam-generators; and the primary object thereof is to provide improved circulation in an ordinary boiler and to prevent incrustation of the shell of the boiler and to provide a positive circulation of the water through the same and also to provide means whereby water may be more quickly heated and steam more quickly and rapidly generated than under ordinary circumstances; and with these and other objects in view the invention consists in an improved water-heater, water-circulator, and steam-generator for steam-boilers, constructed and applied as hereinafter described and claimed.

The invention is an improvement on the construction described and claimed in United States Letters Patent No. 447,866, granted to me March 10, 1891, and is fully described in the following specification, of which the accompanying drawing forms a part, in which the separate parts of my improvement are designated by suitable reference characters, said drawing being a perspective view of an ordinary boiler provided with my improvement.

In the drawing forming part of this specification I have shown at *a* an ordinary tubular boiler, which is mounted in the usual manner in a furnace comprising side walls *b*, a rear end wall *c*, and a front end wall *d*, and in the front end portion of which is a fire-chamber *e*, beneath which is a grate *f*, beneath which is the usual ash-pit *g*, and rearwardly of the grate *f* and forming the rear wall of the fire-chamber and ash-pit and a partial support for the grate is a transverse bridge-wall *h*, the top of which is a predetermined distance above the grate *f*. The front wall *d* is also provided with the usual doors *i* and *j*, which afford access to the fire-box and ash-pit.

In the practice of my invention I provide a supplemental water-heater, water-circula-

tor, and steam-generator, in the construction of which I employ a transverse water-box *k*, located beneath and preferably slightly in front of the front end of the boiler, and this water-box is connected with the front end of the boiler, near the top thereof, by means of pipes *k*². Connected with the water-box *k* and extending backwardly beneath the boiler are a plurality of pipes *k*³, and arranged transversely beneath the boiler and resting on the bridge-wall *h* is a water-drum *k*⁴, with which the pipes *k*³ are connected by means of elbow-couplings *k*⁵. The pipes *k*³ are arranged in the same horizontal plane, and the rear ends thereof by means of the couplings *k*⁵ are curved downwardly, and connection between the said pipes and the water-drum *k*⁴ is made in the top portion of said drum. Connected to the rear side of the water-drum *k*⁴ and preferably centrally thereof is a pipe *k*⁶, the rear end of which is connected with the vertically-arranged pipe *k*⁷, the upper end of which is connected directly with the bottom of the boiler, at or near the rear end thereof, and the lower end of this pipe is connected with a mud-drum *k*⁸. One or both ends of the water-drum *k*⁴ is provided with a blow-off *m*, and the mud-drum *k*⁸ is also provided with a blow-off *n* and with a hand-hole *o*, closed in the usual or any desired manner.

In the drawing forming part of this specification one of the side walls of the furnace is removed; but it will be understood that the blow-off *m* of the water-drum *k*⁴ is provided with a pipe which is carried through the side wall of the furnace, and both ends of said drum may be similarly provided, and the blow-off *n* of the mud-drum *k*⁸ is also provided in practice with a pipe which is carried through the wall of the furnace. As thus constructed it will be seen that the water-drum *k*⁴, which forms a part of the supplemental heater, circulator, and steam-generator, also forms a part of the rear wall of the fire-chamber *e*, and the flames and hot gases from the said fire-chamber strike against this water-drum and pass over it and also pass between the tubes *k*³ and around the tube *k*⁶, and these parts are therefore highly heated, and the pipes *k*² and *k*⁷, being connected with the boiler as shown and described, are kept full of water at all times, as is also the water-box

k and water-drum *k*⁴, and by reason of the connection of the pipes *k*² and *k*⁷ with the boiler in the manner described and the relative arrangement of the other parts of the supplemental heater, circulator, and steam-generator the water is forced to circulate freely and rapidly through the boiler and through the various parts of the supplemental heater, circulator, and steam-generator.

- 10 My invention is in no way limited to the particular form of the furnace, nor to the method of supporting the boiler therein, nor to the method of connecting the separate parts of my improvement, and the box *k*, the pipes *k*² and *k*³, the drum *k*⁴, the pipe *k*⁶, and the pipe *k*⁷ may be connected in any desired manner, and instead of using but one pipe between the drum *k*⁴ and the pipe *k*⁷ a plurality of such pipes may be employed, and 15 these parts may all be so connected as to be capable of being separated when desired for the purpose of cleaning, repairing, &c. By means of this construction there is a positive, direct, continuous, and unobstructed flow of 20 water in one direction, the water being taken from the lower rear part of the boiler and returned thereto at the upper front portion thereof, and this circulation is such as to prevent a deposition of dirt, sediment, or similar substances on the inner surface of the 25 boiler and also on the inner surfaces of the parts of the supplemental heater, water-circulator, and steam-generator, and it will be apparent that by reason of the construction 30 herein described steam may be quickly generated within the boiler and a high pressure of steam secured at a comparatively slight expense of fuel.

Having fully described my invention, what 35 I claim as new, and desire to secure by Letters Patent, is—

1. A water-heater, circulator, and steam-generator for steam-boilers, comprising a transverse water-drum arranged rearwardly 40 of the fire-chamber of the furnace and supported on the bridge-wall of the furnace, a water-box placed transversely of and beneath the front end of the boiler, horizontally-arranged pipes connected with said water-box 45 and with the top portion of said drum, other pipes connecting the water-box with the front end of the boiler near the top thereof, a vertically-arranged pipe connected with the bot-

tom portion of a boiler at the rear end thereof and in communication with said water-drum, 55 and a mud-drum connected with the lower end of the vertically-arranged pipe, substantially as shown and described.

2. A water-heater, circulator, and steam-generator for steam-boilers, comprising a transverse water-drum arranged rearwardly 60 of the fire-chamber of the furnace and supported on the bridge-wall of the furnace, a water-box placed transversely of and beneath the front end of the boiler, horizontally-arranged pipes connected with said water-box 65 and with the top portion of said drum, other pipes connecting the water-box with the front end of the boiler near the top thereof, a vertically-arranged pipe connected with the bottom portion of a boiler at the rear end thereof 70 and in communication with said water-drum, and a mud-drum connected with the lower end of the vertically-arranged pipe, said mud-drum being also provided with a hand-hole 75 and blow-off, substantially as shown and described.

3. A water-heater, circulator, and steam-generator for steam-boilers, comprising a transverse water-drum arranged rearwardly 80 of the fire-chamber of the furnace and supported on the bridge-wall of the furnace, a water-box placed transversely of and beneath the front end of the boiler, horizontally-arranged pipes connected with said water-box 85 and with the top portion of said drum, other pipes connecting the water-box with the front end of the boiler near the top thereof, a vertically-arranged pipe connected with the bottom portion of a boiler at the rear end thereof 90 and in communication with said water-drum, and a mud-drum connected with the lower end of the vertically-arranged pipe, said mud-drum being also provided with a hand-hole 95 and blow-off, and the water-drum being also provided with a blow-off, substantially as shown and described.

In testimony that I claim the foregoing as my invention I have signed my name, in presence of the subscribing witnesses, this 28th day of March, 1903.

JAMES J. BUSH.
